UNITED STATES PATENT OFFICE.

GEORGE AINSWORTH, OF GREAT NECK, NEW YORK, ASSIGNOR TO BEVERLY LIGHTS CORPORATION, OF PROVIDENCE, RHODE ISLAND, A CORPORATION OF RHODE ISLAND.

DESIGN FOR A CANDLE CUP FOR LIGHTING FIXTURES.

Application filed September 22, 1922. Serial No. 3,794. Term of patent 14 years.

To all whom it may concern:

Be it known that I, GEORGE AINSWORTH, a citizen of the United States, and residing at Great Neck, in the county of Nassau and State of New York, have invented a new, original, and ornamental Design for a Candle Cup for Lighting Fixtures, of which the following is a specification, reference being had to the accompanying drawing, forming part thereof.

Fig. 1 is a side elevation of a candle cup for lighting fixtures showing my new design.

Fig. 2 is a bottom view of the same.

I claim:

The ornamental design for a candle cup for lighting fixtures, as shown.

GEORGE AINSWORTH.
